Africa, November 21, 1942

13 Claims. (Cl. 13—23)

1

This application is a division of my application Serial No. 478,375, filed on March 8, 1943.

This invention relates to salt bath furnaces.

Salt bath furnaces have been found advantageous for heating the cutting ends of rock drill tools; and furnaces have been devised in which such tools are arranged in a substantially vertical position with their cutting ends downward and dipped below the surface of the bath material only so far as the ends require to be heated for forging or tempering them as the case may be. The invention consists in improvements in this kind of furnace having as their object increase of the throughput of the furnace and reduction of labour in ensuring that the proper depth of immersion is attained.

For instance, in bath furnaces heretofore devised for heating the lower ends of rock drill tools and other rod-like bodies in the manner described, the bodies had to be suspended from insulating supporting means above the bath and kept from contact with one another; and the means to ensure the immersion of the lower ends only to the predetermined extent has been somewhat cumbersome and has delayed the transfer of the drills to the next operation. This difficulty is overcome according to the invention by providing, in the bath well, a support positioned in the well above the bottom of the well and below the working level of the surface of the bath material and forming a rest for bodies placed in the bath material, said rest being sufficiently near to said working level to limit the immersion of the ends to that requisite for the object of the heating, viz: the aforesaid forging or tempering. The bath level is kept at a substantially uniform height above the support; and the correctness of the level is easily checked by observing the extent of the heated length of the drills as they are withdrawn from the furnace.

A further improvement useful in connection with the heating of rock drill tools is that the well is provided with a cover having aperturing no larger than is convenient for the drills to pass through into the bath; thus conserving the heat of the bath.

When operating at high temperature appreciably in excess of the fusing temperature of the salts used it is desirable to get rid of the fumes that arise from the bath and the invention provides an arrangement for doing this in an effective manner that prevents the great loss of heat when the well cavity is directly ventilated so that cold air is drawn into it. For this purpose the bath well is substantially enclosed ex-

2

cept for the above-mentioned cover aperturing; and there is provided an exhaust duct having its inlet mouth positioned to collect gas tending to pass from the interior of the well to the open air, through said aperturing.

It is necessary to provide some means of steadyng the upper portions of long drills when their lower ends rest on the support. There is provided for this purpose a rest positioned at a higher elevation than the furnace cover and providing, in plan, a gap having an open end and a closed end, the latter displaced to one side of the cover slot and spaced from the open end in the direction of such displacement.

15 The invention is illustrated in the accompanying drawings in which

Figure I is a perspective view of a rock drill heating furnace with parts broken away to show the interior.

20 Figure II is a vertical section transverse to the length of the furnace.

The bath structure shown in Figures I and II comprises walls 2 and a base 3 of heat resisting material, enclosing a bath well 4. In the regular use of the furnace said well contains a mass 5 of molten salt with its surface at about the level a—a. For the purpose of heating simultaneously a number of rock drill tools 6 arranged in a row, it is convenient to make the well considerably longer than its width.

A cover 7 closes in the well cavity to a large extent and so prevents loss of heat from the bath as well as shielding the operator from radiated heat. The drill tools 6 require to be heated only at their cutting ends 8. The cover is accordingly provided with a longitudinal slot 9 suitable to receive a row of drill tools with the lowered ends submerged in the bath and no wider than is reasonably necessary for that purpose; or there may be a row of holes equivalent to a slot.

35 The bath heating elements are indicated by 10 and 11 respectively, and are shown positioned one above the other; the element 10 resting on the base 3 of the bath well with its terminals 45 12, 13 extending up through slots 14 in the ends of the bath structure. Said elements are about as long as the bath well.

In the combination of elements here shown, the elements 10 and 11 are arranged to heat the bath electrically after the bath material has been melted, but element 10 may be arranged to melt the bath material by resistance heating.

Element 11 serves as a support for the tools 6, a datum level for determining the level at which the bath surface should be maintained,

and a shield to prevent accumulation of foreign matter in the bottom of the well.

The element 11 is a simple plate that rests removably and in a horizontal position on shoulders 15 provided by the walls 2 of the bath structure. In the use of the bath, the amount of the bath material is so regulated that it submerges plate 11. Element 10 being at the bottom of the well is also totally submerged, so that neither electrode intersects an air-salt interface.

The tool ends 8 rest on the plate 11 and the depth of molten salt above the upper surface of said plate is regulated according to the length of the lower end of the tools that is to be directly heated by immersion in the salt, say one half inch for hardening or one and a half to two inches for forging.

A result of supporting the tools on the upper side of plate 11 is that they are well out of the electric circuit. This gives the important advantage that there is no material difference of electrical potential between the several tools of a batch, which would necessitate their being insulated from one another. A second important advantage is that variation of the number of tools inserted into the bath does not interfere with the electrodic heating.

In salt baths in which the electrodes project above the surface level and intersect the air-salt interface, slight changes of the level of the bath alter the electrode area in contact with the salt, and consequently the magnitude of the resistance to the electrodic heating current and the temperature of the bath. This instability is serious enough to make it customary to install pyrometer control of the current, necessitating control devices which form a considerable percentage of the total cost of the furnace. In the present case, the fact that the bath level is well above the electrodes avoids any variation of the effective electrodic area; with the result that no expensive temperature control device is necessary when the line voltage is reasonably constant.

One of the difficulties of heating ferrous articles in salt bath furnaces heretofore has been due to scale detaching itself from the articles and accumulating in the bottom of the bath well. The plate 11 constitutes a shield for the bath well and itself receives the deposit of scale, which can readily be scraped up from time to time for removal. This shielding function necessitates some channel by which the salt above and below the plate is kept in free communication; and there is shown for this purpose grooving 16 in the upper surface of the shoulders 15 leading to longitudinal grooves 17 beyond the long edges of plate 11. Said grooves 17 form gutters into which foreign matter that may spill off the edges of plate 11 is received without tending to pass into the grooving 16 and from which grooves such matter can readily be scraped out.

As has been pointed out, the weight of the drills 6 is carried by the plate 11; and the length of the heated zone of the cutting ends is determined by the depth to which 11 is submerged in the molten bath material; consequently the elaborate drill supporting means heretofore used and comprising means adjustable according to the length of each drill, can be done away with. All that remains to be provided is a simple means of engaging the upper portions of the drills to prevent their toppling over. For this purpose gapped rests are provided at a higher elevation than the furnace cover and to one side thereof,

and such that upon the drills being tilted somewhat from the vertical their upper portions rest stably by gravity in said rests. Referring to the drawings a pair of posts 18 is erected at the ends of the furnace structure for the purpose of supporting a pair of racks 19, 19a. Each rack consists of a horizontal rack bar 20 and 20a having at its ends lugs 21, 21a, for attaching it to the posts. The posts are slotted at 22 to enable the racks to be secured at various heights according to the average length of the drills under treatment. Each bar is provided with a series of horizontally extending fingers 23, 23a providing between them the recesses 24, 24a into which the drill stems are passed by tilting them. To cause the drills to be inclined when within said recesses, the lugs 21a of the upper rack 19a are of such length as to set the bar 20a back from the slot 9 in plan; and the lugs 21a are longer than the lugs 21 so as to set the bar 20 not so far back, in accordance with the inclination of the drills. The two racks are provided to keep the drills parallel with one another in the plane of the slot 9; but if the slot 9 is replaced by an equivalent series of holes, one of the racks may be omitted.

One of the difficulties attending the operation of salt bath furnaces and particularly drill heating furnaces in the past has been concerned with the disposal of the fumes that arise from the hot salt. The ventilating arrangements heretofore used have been such as to set up an air current through the well; but it has been found that the resulting loss of heat seriously diminishes the efficiency of the furnace.

To avoid this loss, the bath well is kept closed except for the slot 9. Hot gas and fumes accordingly tend to escape through said slot; but they are collected and prevented from passing into the open air by an exhaust duct comprising a series of holes 25 extending from one side wall 26 of the slot 9 and through the body of the cover 7 to the edge 27 of the cover where they join flue channelling 28 formed in the furnace structure. Said channelling leads to a chimney 29 which creates a draft, through the holes 25 and channelling 28, and so causes the fumes to be withdrawn continually from the bath. The exhaust duct may be also placed immediately above and in alignment with the longitudinal slot.

I claim:

1. An electrically heated salt bath furnace suitable for heating the ends of steel bodies, comprising a well for the bath material, a support positioned in the well above the bottom of the well and below the working level of the surface of the bath material and forming a rest for bodies placed in the bath material, said rest being sufficiently near to said working level to limit the immersion of the ends to that requisite for the object of the heating.

2. The furnace claimed in claim 1, comprising a heating element shaped and arranged to form the support.

3. The salt bath furnace claimed in claim 1, in which the well is provided with a cover adapted to remain in position while rod-like bodies are inserted into and withdrawn from the furnace, said cover providing an aperturing suitable for the lower ends of rod-like bodies to be passed through it but of substantially less horizontal area than the horizontal area of the bath surface, the well being substantially closed-in except for this aperturing, and comprising an exhaust duct having its inlet mouth positioned to collect gas tending to pass to the open air through said aperturing,

said exhaust duct comprising means to set up a ventilating current from its intake end next to the cover aperture to its discharge end, which latter is positioned to discharge the current clear of the furnace.

4. The salt bath furnace as claimed in claim 1, and suitable for heating the ends of rod-like bodies such as rock drill tools, comprising means elevated above the well for loosely engaging the upper ends of rod-like bodies and thereby in conjunction with the rest to hold such bodies stably in a position that is sufficiently vertical to avoid material extension of the aforesaid limitation of the immersion of their lower ends.

5. The salt bath furnace as claimed in claim 1, and suitable for heating the ends of rod-like bodies such as rock drill tools, comprising means elevated above the well for loosely engaging the upper ends of rod-like bodies and thereby in conjunction with the rest to hold such bodies stably in a position that is sufficiently vertical to avoid material extension of the aforesaid limitation of the immersion of their lower ends; said elevated means providing in plan a gap having an open end and a closed end, the latter being displaced to one side of the cover aperturing and spaced from the open end in the direction of said displacement, so that stable gravitational support of the elongated bodies is obtained by the lower ends resting on the support and their upper ends leaning into the gap.

6. An electrically heated bath comprising a well for bath material and electrical heating means comprising a resistance element and another electrically conducting element arranged in said well, in which the resistance element is arranged in the lower part of the well and in which the other element is a plate positioned horizontally between said resistance element and the mouth of the well so as to form a rest for articles dipped in the bath material and to shield the lower part of the well, and comprising means for maintaining communication between liquid bath material above and below the plate.

7. An electric heating bath comprising a well containing an electrolyte, a pair of superposed electrical conductors in said bath, the lower conductor providing ohmic resistance for the melting of the electrolyte, and the upper conductor serving as a support for articles immersed in the electrolyte and to be heated.

8. An electric heating apparatus comprising a vessel adapted to contain an electrolyte, a pair of superposed electrodes in said vessel and below the normal liquid level of the electrolyte, the upper electrode being adapted to support the lower ends of substantially vertically disposed rod-like articles immersed in said vessel and to be heated, and to limit the extent to which the lower ends of the articles may be immersed in the bath.

9. An electric heating apparatus comprising a vessel adapted to contain an electrolyte, a pair of superposed electrodes in said vessel and below

the normal liquid level of the electrolyte, the upper conductor being adapted to support the lower ends of substantially vertically disposed rod-like articles inserted in said vessel and to be heated, and to limit the extent to which the lower ends of said articles may be inserted in the bath, a cover on said vessel having a slot through which the articles to be heated may be inserted, and a rack for holding said articles in substantially vertical positions.

10. A bath comprising a well for containing molten bath material, a cover for the well providing an aperture of small area compared with the horizontal area of the well for the insertion therethrough of the lower ends of rod-like articles to be heated in the bath, and a pair of superposed electrodes in the well below the surface of the bath, the upper of said electrodes serving as a support for limiting the extent to which said articles may extend into the well.

11. An apparatus for electrically heating the ends of rod-like articles, comprising a well for bath material, electrical means within the well for heating the bath and including a horizontally disposed electrode serving as a support for the lower ends of said articles and limiting the extent to which said articles may be inserted in the bath, a cover for said well having a slot through which the lower ends of the articles may be inserted in a row, and a rack above said cover for engaging the upper portion of said articles to space them and hold them in substantially vertical positions.

12. An apparatus for electrically heating the ends of rod-like articles, including a well adapted to contain molten bath material, superposed electrodes within the well and beneath the surface of the bath, the upper of said electrodes serving as a support for said articles, said well having a cover provided with a slot through which a row of said articles may be inserted into the bath to rest upon said upper electrode and a rack above said cover for holding said articles in spaced substantially vertical positions.

13. An electrically heated bath comprising a well for bath material and electrical heating means comprising a pair of electrical conducting elements within the bath, one of said elements being in the form of a plate positioned horizontally and serving as a support for articles dipped into the bath and providing communication between the liquid bath above and below the plate, and means above said well for engaging the upper parts of the articles to be heated and for holding them in substantially vertical positions.
